UNITED STATES PATENT OFFICE.

JOHN H. FOWLER, OF LEWISTOWN, PENNSYLVANIA.

SUPPORTING-BRACKET.

1,348,399.

Specification of Letters Patent.

Patented Aug. 3, 1920.

Application filed October 11, 1919. Serial No. 329,928.

To all whom it may concern:

Be it known that I, JOHN H. FOWLER, a citizen of the United States, residing at Lewistown, in the county of Mifflin and 5 State of Pennsylvania, have invented certain new and useful Improvements in Supporting-Brackets, of which the following is a specification.

This invention relates to supporting 10 brackets particularly designed for use in supporting window shades, pictures or analogous articles, and an object of the invention is to provide a bracket structure which embodies a foundation or main body of wood or 15 analogous material which has a carrying socket attached thereto, the said carrying socket being formed of a strip of sheet metal, which strip is further bent to extend over an arcuated portion of the body of the 20 bracket structure to form a guide to lead the portion of the article to be supported into the socket of the bracket structure.

Another object of the invention is to provide, in a supporting bracket as specified, 25 attaching means adapted to extend one into the support at right angles thereto and a second attaching member which is adapted to extend diagonally through the body of the bracket structure and into the support at 30 an oblique angle with respect to the right angularly extending attaching member which latter or diagonally extending attaching member further serves to assist in attaching the metal guide and socket to the 35 main body of the socket structure.

Other objects of the invention will appear in the following detailed description taken in connection with the accompanying drawing, forming a part of this specification, and 40 in which drawing:

Figure 1 is a side elevation of a supporting bracket.

Fig. 2 is a side elevation of a supporting bracket adapted to coact with the supporting bracket illustrated in Fig. 1 to form a set of brackets to support the roller of a window shade.

Figs. 3 and 4 illustrate side elevations of a set of modified forms of the bracket structures, these brackets being adapted to support the opposite ends of a window shade roller.

Fig. 5 is a side elevation of still another modified form of the supporting bracket.

Fig. 6 is a front elevation of the supporting bracket illustrated in Fig. 5.

Fig. 7 is a side elevation of a further modification of the supporting bracket illustrating the companion bracket of a set, adapted to be used with the supporting 60 bracket illustrated in Fig. 5.

Fig. 8 is an edge elevation of the supporting bracket illustrated in Fig. 7.

Fig. 9 is a side elevation of a supporting bracket particularly adapted for supporting 65 pictures or analogous articles suspended by flexible supports or cords, and

Fig. 10 is a front elevation of a supporting bracket illustrated in Fig. 9.

Referring more particularly to the drawings, the supporting brackets illustrated in Figs. 1 and 2 which form a set, designed for supporting the opposite ends of the spring roller of window shades, each comprise a body 20 formed of wood or analogous material, which body is provided with a convex upper surface 21, the lower end of which merges into the concaved surface 22 formed upon the upper edge of the laterally projecting extension 23 of the body. From the 70 under surface of the extension 23, the lower edge of the body inclines downwardly and inwardly, the said body having a depending extension or lug 24 upon its lower end, the outer surface of which is parallel to the inner or back edge 25 of the body and adapted to lie parallel with the permanent support indicated at A to which the bracket body 20 is to be attached. A screw or analogous attaching device 26 is inserted through the 75 extension 24 and extends into the support at 80 right angles to the face thereof.

The main body 20 of the bracket illustrated in Fig. 1 of the drawings has a metal pocket 27 attached thereto which 95 pocket is adapted to receive the substantially rectangular end or pintle of an ordinary curtain shade roller. This pocket 27 is formed by the bending of one end of a strip 28 of sheet metal into a substantially 100 U-shape as clearly shown in Fig. 1, while the main portion of the strip 28 of metal is concavo-convexly curved to lie snugly against the convexed surface 21 of the body 20, forming a metal guide for guiding the 105 rectangular pintle end of a curtain shade roller into the pocket 27. This strip 28 is attached to the body 20 by a nail or analogous fastening device 29 and also by the attaching nail 30, which extends diagonally 110 through the body 20 near the upper end thereof, and also extends diagonally into the

permanent support A, and at an obtuse angle to the screw or analogous attaching device 26, thereby the nail 30 serves the dual function of attaching the metal strip 28 to the body 20 and attaching the entire supporting bracket structure to the permanent support A. In Fig 2 of the drawings, the main body of the bracket is identical in construction with the body of the form illustrated in Fig 1, this form differing from the form illustrated in Fig 2 only in the shaping of the pintle receiving portion of the metal strip 31 thereof. The major portion of the metal strip 31 is concavo-convexly curved for fitting the curved upper edge 21 of the body 20 of the form illustrated in Fig. 2 of the drawings, but its lower end is rolled to form a substantially circular socket 32 adapted to receive the round and rigid pintle of an ordinary spring curtain shade roller therein.

In Figs. 3 and 4 of the drawings, a modified form of the supporting bracket is illustrated. These modified forms comprise a main body 40 constructed of wood or any analogous material, so as to lend a firm and rigid supporting body to the bracket structure. However, the outer edge of the body 40 is provided at its uppermost portion with outwardly inclining edge or surface 41, the lower edge of which merges by means of a convexed portion 42 into the upper edge of a concavely curved portion 43. This concavely curved portion 43 terminates or merges at its lowermost portion into a substantially straight surface 44 which is parallel to the inner or back edge 44 of the body 40, and the lower end of the straight portion 44 merges into the concavely curved portion 46 formed in the upper end of the lateral extension 47 formed at the lower end of the body 40. The concavely curved portion 46 forms a shoulder for supporting the bight portion of the substantially U-shaped socket 48, in the form illustrated in Fig. 3 of the drawings. This substantially U-shaped socket 48 is provided for receiving the substantially rectangular pintle of an ordinary spring roller or for receiving the suspending cord of a picture or analogous article and it is formed by the bending of one end of a metal strip 49 into substantially U-shape, while the major portion of the strip 49 is shaped to lie in facial abutment with the various outlines of the outer end of the body 40 as clearly shown in the drawings. A screw or analogous attaching device 50 is inserted through the metal strip 49 and the body 40 at substantially intermediate the ends of the concaved portions thereof, and this screw extends into the permanent support B substantially at right angles to the outer face thereof, and also substantially at right angles to the back edge 65 of the body 40. The screw 50 further

serves to attach the strip 49 to the body 40. The strip 49 is further attached to the body 40 by means of a nail, pin or analogous structure 51 and by the nail or pin 52. This latter nail or pin 52 extends diagonally through the body 40 and substantially at right angles to the inclined portion 41 of the outer edge thereof, extending into the permanent support B at an oblique angle to the screw 50. The major portion of the strip 49 of sheet metal is shaped to form a guide for guiding the article to be engaged in the socket 48, thereinto, so that it need not be exercised in placing the article to be supported within the socket, which consequently eliminates much of the exasperating and difficult work of positioning the rectangular spring shade roller in its supporting bracket, as is caused by the use of the shade roller brackets of approved form.

The form illustrated in Fig. 4 of the drawings is similar to the form illustrated in Fig. 3 of the drawings, being the companion bracket of the set and differing therefrom only in the shape of the socket. In Fig. 4, this socket 48^a is circular in cross section it being shaped to receive therein the round or cylindrical pintle of a shade roller.

A further modification of the supporting bracket is illustrated in Figs. 5 to 8 inclusive, which figures illustrate a set of supporting brackets adapted to support the respective pintles of a spring roller of approved form generally used upon window shades. These modified forms comprise the main body 60 which is constructed of wood or suitable material and which has substantially the same outline as the bodies 20 illustrated in Figs. 1 and 2 of the drawings. These forms illustrated in Figs. 5 to 8 differ from the form illustrated in Figs. 1 and 2 only in the metal portions thereof.

The forms illustrated in Figs. 5 and 6 of the drawings, have the open socket 61 which is designed for receiving the rectangular pintle of a shade roller or the supporting cord of a picture, plaque or analogous article. This open end of the substantially U-shaped socket 61 is formed upon one end of the piece 62 of sheet metal and this piece of sheet metal is shaped to form a portion 63 which lies in facial abutment with the upper convexly curved portion of the body 60 and the portion 63 has substantially right angularly bent flanges 64 which engage against the sides of the body 60 adjacent the convexed upper edge thereof. The body 60 may have one side thereof angled, as shown in Fig. 6 of the drawings so that the thickness of the body will gradually increase as it extends toward the back edge 65 of the body. However, the face or side of the body facing the end of the curtain roller to be supported thereby is perfectly flat, and as clearly shown in Figs. 6 and 8 of the

drawings, the bodies of the bracket of a set have their opposite side angles or inclining toward their back edges 65 so as to present perfectly flat edges toward each other. 5 In the form illustrated in Fig. 8 of the drawings which is the companion bracket of the set including the forms illustrated in Figs. 5 and 6 the metal protector 66 is provided with a concavo-convexly curved portion 10 for lying in facial abutment with the upper convexed edge of the body 60 and with laterally bent flanges 67 which engage upon the sides of the body 60 adjacent the curved edge portion thereof. These flanges 15 67 are provided with enlargements 68 at their lower ends, which enlargements are provided with circular openings 69 alining with each other and being positioned directly above the concavely curved portion 20 70 of the body which corresponds to the concavely curved portion 22 of the body 20. These openings 69 are adapted to receive therethrough the round pintles of a curtain shade roller to support the latter in connection 25 with the open substantially U-shaped socket 61.

The body 20 and 40 may also have one side inclining outwardly toward their rear or back edges if desired, without departing 30 from the spirit of this invention.

The modified form illustrated in Figs. 9 and 10 of the drawings is particularly designed for use as a support for pictures, plaques or analogous articles and it comprises a main body 75 constructed of wood or analogous material which gradually increases in thickness from its outer edge to its inner or back edge 76. This body 75 is provided with a convexly curved edge portion 77 which merges into the concaved portion 78 formed in the upper edge of the lateral extension 79 of the body. The body inclines downwardly and inwardly toward the rear or back edge 76 thereof from the 45 outer edge of the lateral extension 77 and a depending extension 80 is formed upon the lower edge of the body which receives therethrough the screw or analogous attaching device 81. This screw extends into the permanent support C at right angles thereto, 50 while a second attaching member such as a nail or the like 82 extends into the permanent support C at an oblique angle to the screw 81. This nail 82 serves to assist in attaching the strip of sheet metal 83 to the convexed edge portion 77, which gradually decreases in width as it extends downwardly over the convexed edge 77 as clearly shown in Fig. 10 of the drawings terminating at 55 its lower end in a substantially U-shaped socket 84 which is adapted to receive therein, the cord or supporting wire D of a picture, plaque or analogous article. As clearly shown at 85, in Figs. 9 and 10 of the drawings, the bight portion of the substantially

U-shaped socket 84 is convexly curved, so as to eliminate corners or sharp edges which would have a tendency to cut the cord D. A second nail or analogous fastening device 86 is provided for assisting the nail 82 in attaching the metal strip 83 to the body 75. 70

Changes in details may be made without departing from the spirit of this invention, but;

I claim:

1. In a supporting bracket, the combination of a solid body including a lateral extension on its outer edge having a concaved edge, and a metal socket carried by the body and resting on said concaved edge. 75 80

2. In a supporting bracket, the combination of a solid body including a lateral extension on its outer edge having an upper concaved edge, a metal socket carried by the body and resting on said concaved edge, the edge of said body leading to said socket being curved to form a guiding lead therefor. 85

3. In a supporting bracket, the combination of a wooden body including a lateral extension on its outer edge having an upper concaved edge, an attaching member extending through the body at right angles to the back thereof, and a second attaching member extending through the body in an oblique angle to the first attaching member. 90

4. In a supporting bracket, the combination of a wooden body including a lateral extension on its outer edge having an upper concaved edge, an attaching member extending through the body at right angles to the back thereof, a second attaching member extending through the body at an oblique angle to the first attaching member, and a metal socket carried by the body and resting 100 105 on said concaved edge.

5. In a supporting bracket, the combination of a solid body including a lateral extension on its outer edge having an upper concaved edge, the outer edge of said body leading to said concaved edge being curved, 110 a metal strip lying in facial engagement with said curved portion and being shaped to form a socket resting upon said concaved edge. 115

6. In a supporting bracket, the combination of a solid body including a lateral extension on its outer edge having an upper concaved edge, the outer edge of said body leading to said concaved edge being curved, 120 a metal strip lying in facial engagement with said curved portion and being shaped to form a socket resting upon said concaved edge, an attaching member extending through the body at right angles to the back thereof, and a second attaching member extending through the body at an oblique angle to the first named attaching member and assisting in attaching said metal strip to the body. 125 130

7. In a supporting bracket, the combination of a solid body including a lateral extension on its outer edge having an upper concaved edge, the outer edge of said body leading to said concaved edge being curved, a metal strip lying in facial engagement with said curved portion and being shaped to form a substantially U-shaped socket opening upwardly and resting upon the concaved edge.

8. In a supporting bracket, the combination of a solid body including a lateral extension on its outer edge having an upper concaved edge, the outer edge of said body leading to said concaved edge being curved, a metal strip lying in facial engagement with said curved portion and being shaped to form a substantially U-shaped socket opening upwardly and resting upon the concaved edge, and substantially right angularly extending flanges formed on said metal strip and being bent to engage the sides of said body.

9. In a supporting bracket, the combination of a wood body including a lateral extension on its outer edge having an upper concaved edge, the outer edge of said body leading to said concaved body being curved, a metal strip lying in facial engagement with said curved portion and being shaped to form a socket resting upon said concaved edge, one side of said body gradually in-

clining outwardly toward the back edge thereof.

10. In a supporting bracket, the combination of a wooden body including a lateral extension upon its outer edge having an upper concaved edge, a depending extension on its lower edge, an attaching member extending through said depending extension at right angles to the back of the body, the outer edge of said body leading to said concaved edge being convexly curved, a metal strip lying in facial engagement with said curved position and being shaped to form a socket resting upon said concaved edge.

11. In a supporting bracket, the combination of a wooden body including a lateral extension upon its outer edge having an upper concaved edge, a depending extension on its lower edge, an attaching member extending through said depending extension at right angles to the back of the body, the outer edge of said body leading to said concaved edge being convexly curved, a metal strip lying in facial abutment with said curved portion and being shaped to form a socket resting upon said concaved edge, and a second attaching member extending through said metal strip and said body at an oblique angle to the first named attaching member.

JOHN H. FOWLER.
